DISPENSING DEVICE

Nathan W. Holbrook, Nashville, Tenn.

Application October 23, 1951, Serial No. 252,728

2 Claims. (Cl. 222—330)

1

This invention relates to an improved dispensing device, the primary object of the invention being to provide a simple and efficient device of this kind which is particularly but not exclusively devised for use with cartons for dispensing therefrom uniform amounts of such materials as powdered or granulated soap, condiments and the like.

Another important object of the invention is to provide a device of the character indicated above which includes means for entering and being secured in an opening preferably on the side wall of a carton or the like, provided for by perforations formed in the side wall, whereby the device is securely and removably mounted in operative relation to the carton or the like.

Another important object of the invention is to provide a valved device of the above-indicated character which in the operation of its valve imparts a swirling, scattering motion to the material being dispensed, which prevents clodding and lumping of the material being dispensed.

Other important objects and advantageous features of the invention will be apparent from the following description and the accompanying drawings, wherein, for present purposes of illustration only, a specific embodiment of the invention as set forth in detail.

In the drawings:

Figure 1 is a side elevation;

Figure 2 is a top plan view;

Figure 3 is a bottom plan view;

Figure 4 is a longitudinal section taken on the line 4—4 of Figure 2;

Figure 5 is a transverse section taken on the line 5—5 of Figure 1; and

Figure 6 is a perspective view showing the device installed in an opening in a carton side wall.

Referring in detail to the drawings, wherein like numerals designate like parts throughout the several views. The illustrated device comprises a tubular, cylindrical body 9 formed with a preferably integral, external, annular stop flange 10 located about midway between its inner and outer ends 11 and 12, respectively.

The inner end 11 of the body 9 is internally beveled at 14 to a sharp edge 15 which facilitates penetrating the side wall 16, or other wall of a carton 17 or other container preferably provided with perforations defining a dispensing hole through which the inner end 11 of the body 9 is adapted to be inserted.

The exterior of the body 9 between the stop flange 10 and the inner end 11 is formed with longitudinally elongated, radially projecting fins

or lugs 18 at widely spaced, circumferential intervals. The lugs 18 have outer edges 19 which taper toward the inner end 11 of the body 9 to facilitate their entry into the hole formed in a carton side wall, and the wider outer ends 20 of the lugs are longitudinally spaced from the stop flange 10 to define shoulders arranged to engage the inner surface of the container wall in opposition to the stop flange 10 which is arranged to engage the outer surface of the carton side wall, a secure mounting of the dispensing device on the carton thus being assured.

Internally the body 9 is provided with a partition disc 21 which is located intermediate the ends of the body 9 and forms a material-accommodating chamber 22 between itself and the inner end 11 of the body 9. The partition disc 21 is formed with two diametrically opposed, fan-shaped openings 23, 23 which provide limited communications between the chamber 22 and the cylindrical space 24 in the interior of the body 9 outwardly of the partition disc 21.

In the cylindrical space 24 is positioned the rotary cruciform cross-section valve 25 which has a running fit with the surface of the side wall of the space 24 and extends axially from the outer side of the partition disc 21 to a point close to the outer end 12 of the body 9. The four vanes 26 of the valve 25 are equally circumferentially spaced and have substantially the same circumferential spacing from each other as the side edges of the fan-shaped openings 23 of the partition disc 21. The vanes 26 converge at their rearward ends in an axial hub 27 which has an axial pin 28 on its inner end which is journaled in a hole 29 formed in the center of the partition 21; and another axial pin 30 on its outer end which is journaled in a hole 31 formed in a cover disc or end plate 32 which is inserted in the outer end 12 of the body 9 and has a lateral flange 33 engaging the outer end 12. The outer end portion of the hub 27 of the valve 25 has an eccentric projection 34 provided with an abutment face 35.

The inner surface of the end plate 32 is formed with a transverse groove 36 which extends tangentially to the hub and normal to the abutment face 35 in the normal closed position of the valve 25. A widened inner end portion of the groove 36 defines a stop shoulder 37. A push bar 38 slides lengthwise in the groove 36 and has a lateral stop projection 39 for engaging the stop shoulder 37 to prevent outward displacement of the push bar 38. The push bar 38 has a pressure cup or disc 40 on its exposed outer end

for operative engagement by a finger. The end plate 32 is formed with two diametrically opposed, fan-shaped dispensing openings 41, 41 which are arranged at 90° with respect to and between the similar openings in the partition disc 21.

A spiral spring 42 encircles the outer end of the hub 27 of the valve 25 and has one end anchored in a hole 43 in the end plate 32 and its other end bearing against one of the vanes 26, 10 whereby the valve 25 is normally biased in a direction to engage the abutment projection 39 with the inner end of the push bar 38, in which position the vanes 26 occupy positions intermediate the fan-shaped openings of the partition 15 disc 21 and end plate 32 and prevent material from passing from the chamber 22 to the discharge openings 41 of the end plate 32. However, when the push bar 38 is pushed inwardly, the valve is rotated in one direction against the tension of the spring 42. With the carton tilted toward the dispensing device the chamber 22 is then in communication with the spaces between two adjacent ones of the vanes 26 of the valve, 20 so that material passes into these spaces and can fall from the dispensing openings 41. As the push bar 38 is released and the valve 25 is returned toward initial or normal position, more of the material present in the chamber 22 passes into the spaces between adjacent vanes 26 of the 30 valve 25 and is carried around the valve space and permitted to fall through the dispensing openings 41. As the valve rotates thus in opposite directions, the material being dispensed is carried around within the body 9 and thereby 35 prevented from clodding and lumping and is discharged through the openings 41 in oppositely swirling, scattering streams.

The device is preferably made of molded plastic, with the partition disk 21 and end plate 40 cemented in place. In assembling the device, the disc 21 is first secured in place, then the valve 25, spring 42, push rod 38 are placed in position, and the end plate 32 then cemented in place.

What is claimed is:

1. In a dispensing device, an open ended tubular body, a partition in the interior of said body spaced from one end thereof and defining a granular material receiving chamber, said partition being formed with a pair of diametrically opposed openings, an end plate closing the other end of the tubular body, a rotary axial valve positioned in the space between and rotatably supported in said end plate and said partition, said valve comprising a hub and four radial vanes projecting from the hub at circumferentially spaced intervals, said end plate being formed with a pair of diametrically opposed dispensing openings positioned between the openings of said partition, a stop on said end plate, said valve normally occupying a position in which the vanes are located between the openings in the partition and the openings in the end plate and prevent communication therebetween, and operating means connected with said valve for rotating said valve away from its normal position to a position in which its vanes traverse the partition 60 openings and the dispensing openings so as to

permit material present in said chamber to pass between adjacent vanes to the dispensing openings, said operating means comprising a projection extending radially from said hub, a push rod slidably mounted in said end plate and having one end extending through and beyond the side wall of said body, said rod having its other end engageable with said projection for rotating said valve responsive to the sliding movement of said rod toward said valve, a spring connected to said body and to said valve for biasing said valve to its normal position, and a stop projection on said rod adjacent said other end thereof engageable with said stop on said end plate to limit the movement of said rod away from said valve.

2. In a dispensing device, an open ended tubular body, a partition in the interior of said tubular of said tubular body spaced from one end thereof and defining a granular material receiving chamber, said partition being formed with a pair of diametrically opposed openings, an end plate closing the other end of the tubular body, a rotary axial valve positioned in the space between and rotatably supported in said end plate and said partition, said valve comprising a hub and four radial vanes projecting from the hub at circumferentially spaced intervals, said end plate being formed with a pair of diametrically opposed dispensing openings positioned between the openings of said partition, said end plate being provided with a groove on its internal face extending tangentially with respect to said hub, the end portion of said groove adjacent said hub being wider than the main portion of the groove and connected to said main portion by a shoulder, said valve normally occupying a position in which the vanes are located between the openings in the partition and the openings in the end plate and prevent communication therebetween, and operating means connected with said valve for rotating said valve away from its normal position to a position in which its vanes traverse the partition openings and the dispensing openings so as to permit material present in said chamber to pass between adjacent vanes to the dispensing openings, said operating means comprising a projection extending radially from said hub, a push rod slidably mounted in said groove and having one end extending through and beyond the side wall of said body, said rod having its other end engageable with said projection for rotating said valve responsive to the sliding movement of said rod, and a spring connected to said body and to said valve for biasing said valve to its normal position, the portion of said rod adjacent the other end thereof being complementally shaped to fit the widened end portion of said groove and having a shoulder engageable with the shoulder of said groove to limit the movement of said rod away from said valve.
